UNITED STATES PATENT OFFICE.

HOWARD F. KELSO, OF HOUSTON, TEXAS.

WASTE AND OVERFLOW EQUIPMENT FOR BATHTUBS.

Application filed October 25, 1926. Serial No. 144,138.

This invention relates to new and useful improvements in waste and overflow equipment for bath tubs.

One object of the invention is to provide 5 an apparatus of the character described specially designed for the purpose of controlling the waste outlet of a bath tub.

Another object of the invention is to provide an apparatus of the character described 10 including a novel form of bath tub waste outlet with a novel type of valve controlling the same and a mechanism mounted in the overflow pipe through which said valve may be conveniently operated to open or close 15 said valve.

A further feature of the invention is to provide an equipment of the character described whose parts are readily accessible from the inside of the tub, for repairs, or 20 replacements.

Finally the object of the invention is to provide a bath tub equipment of the character described, and for the purposes stated, which is of novel but simple construction, 25 which may be easily installed, whose parts are readily accessible for repairs or replacements and which is very convenient and efficient in use.

With the above and other objects in view 10 the invention has particular relation to certain novel features of construction, operation and arrangement of parts, an example of which is given in this specification and illustrated in the accompanying drawings, 35 wherein:—

Figure 1 shows a vertical sectional view of the equipment applied to a bath tub.

Figure 2 shows a plan view of the waste outlet connection.

Figure 3 shows a vertical sectional view thereof, taken on the line 3—3 of Figure 2, and

Figure 4 shows a vertical sectional view of an overflow connection taken on the line 45 4—4 of Figure 1.

Referring now more particularly to the drawings, wherein like numerals of reference designate similar parts in each of the figures the numeral 1 designates a bath tub 50 of conventional construction and the numeral 2 designates the waste line incorporated into which there is a T connection 3. The numeral 4 designates a waste outlet elbow which is connected into the T 3 through the outlet pipe 5. The upper side 55 of this elbow has a tapering extension 6

which extends up through the opening in the bottom of the tub at one end and surrounding this extension, and fitted between it and the adjacent part of the tub there is 60 a washer 7 of any suitable material and a thimble 8 is threaded into the elbow 4 and has an outwardly extending flange 9 overlapping the washer 7 and clamping it in place. The lower end of the thimble 8 is 65 flared, as at 10, forming a valve seat and beneath it there is an outwardly opening valve 11 whose upper side is formed to conform to the form of the seat 10. Anchored to the bottom of the elbow are the spaced 70 guides 12, 12, which upstand therefrom and project into the guideways 13, 13, of the valve, provided to receive said guides. These guides are provided to confine the 75 valve to a vertical movement.

The thimble 8 has inside projections, as 14, forming means for engaging a wrench used to screw the thimble 8 in place, or to unscrew it. The thimble 8, as well as the washer 7, the valve 11 and the valve guides 80 12 are accessible from the inside of the tub and by removing said thimble said other parts may be removed for repairs, or replacements. An overflow pipe 15 is connected to the upper end of the T 3 and an 85 overflow elbow 16 is connected to the upper end of the overflow pipe 15, by means of the ball joint 15'. This connection is made by a suitable lock nut 16' and permits a suitable adjustment of said connected parts. 90 The elbow 16 is provided with the annular flange 17 which abuts the outside of the tub 1 and the inner end of said elbow is fitted through a suitable opening in the end of the tub near the top and is outwardly 95 threaded to receive a lock nut 18 which, when screwed home, abuts against the inside of the tub and retains the packing washer 19 in place, as well as securing the overflow elbow to the tub. The washer 19 100 may be removed and replaced from the inside of the tub by removing the nut 18. The inwardly projecting end of the elbow 16 is provided with a spider 20 having a central bearing 21, formed with a side slot 105 22. There is an operating rod 23 whose inner end carries a suitable grip, or handle 24, for turning the same and this rod works through the bearing 21 and its inner end carries the eccentric 25. The slot 22 is provided so that the eccentric of the rod 23 may 110 be readily passed therethrough. The oper-

ating rod 23 has the external annular rib 26 which fits against the bearing 21 and the thimble 27 surrounding the rod 23 and is screwed into the spider 20 and abuts the rib 26 retaining the rod 23 against displacement. There is a cup shaped strainer 28 whose margin abuts the inside of the tub, said strainer being fitted over the outlet opening and the thimble 27 is fitted through the central opening in the strainer and has a projecting flange which abuts against said strainer and holds it in place. The end of the outlet waste elbow 4, opposite the pipe 5, has an extension, as at 30 and has an inside anchor hook 31. A flexible connecting member, such as chain 32, has the end hook 33 which engages over the anchor hook 31 and this chain passes between the guides 12 and lies in the grooves 34 in the under side of the valve 11 and is retained against displacement by said guides and the other end of the chain has a long link 35 which engages over the eccentric 25. This chain is located within the outlet and overflow pipes and is protected thereby. In order to hold the valve 11 closed the handle 24 may be suitably manipulated to exert a pull on said chain through the eccentric 25 and this will lift the valve into closed position. When the eccentric 25 passes center it will engage against the stop 36 so as not to turn far enough to release the chain but to hold it taut and incorporated into the chain there is a pull spring 37 which maintains a tension against said wave valve 11 and when it is desired to empty the tub the handle 24 may be manipulated in the other direction to release the pull on said chain and the valve 11 will thereby immediately drop to open the waste outlet.

While I have shown and described equipment, as applied to a bath tub it is obvious that it is applicable for use in connection with other containers, such as wash basins and the like.

45. What I claim is:—

1. A fluid container having a waste outlet and an overflow outlet, a downwardly opening valve controlling the waste outlet, a flexible member anchored at one end and disposed underneath the valve and means associated with the overflow outlet and to which the other end of said flexible member is attached through which said member may be actuated to alternately close, and permit the opening of, said valve.

2. A bath tub having a waste outlet and an overflow outlet, an actuating rod mounted in the overflow outlet and having an eccentric, a flexible member attached at one end to said eccentric and anchored at its

other end, a valve controlling said waste outlet and mounted on and supported by said flexible member.

3. A bath tub having a waste outlet and an overflow outlet, an actuating rod mounted in the overflow outlet and having an eccentric, a flexible member attached at one end to said eccentric and anchored at its other end to a fixed anchor, a valve controlling said waste outlet and mounted above said flexible member and adapted to be actuated thereby into closed position, and released alternatively.

4. A bath tub having a waste outlet formed with a valve seat, a downwardly opening valve controlling said seat, a flexible member attached to an anchor at one end and disposed underneath and in operative connection with said valve, operative means operatively connected with said flexible member through which said member may be actuated to effect the closing or permit the opening of said valve.

5. A bath tub having a waste outlet formed with a valve seat, a valve controlling said seat, a flexible member attached to an anchor at one end and disposed underneath and in operative connection with said valve, operative means operatively connected with said flexible member through which said member may be actuated to effect the closing or permit the opening of said valve and a guide for limiting the range of movement of the valve.

6. A bath tub having a waste outlet formed with a valve seat, a valve controlling said seat, a flexible member attached to an anchor at one end and disposed underneath said valve, operative means operatively connected with said flexible member through which said member may be actuated to effect the closing or permit the opening of said valve, guide means for limiting the range of movement of the valve, said guide means also forming means for retaining said flexible member in operative connection with said valve.

7. A bath tub having a waste outlet formed with a valve seat, a downwardly opening valve controlling said seat, a flexible member attached to a fixed anchor at one end and extending around underneath said valve, operative means operatively connected with said flexible member through which said member may be actuated to effect the closing or permit the opening of said valve and a yieldable element incorporated into said flexible member.

In testimony whereof I have signed my name to this specification.

HOWARD F. KELSO.
